UNITED STATES PATENT OFFICE.

GEORGE CLEAVELAND CHAPPELL, OF JACKSONVILLE, FLORIDA.

SAFETY BOTTLE-CRATE.

SPECIFICATION forming part of Letters Patent No. 613,441, dated November 1, 1898.

Application filed October 11, 1897. Serial No. 654,786. (No model.)

To all whom it may concern:

Be it known that I, GEORGE CLEAVELAND CHAPPELL, a citizen of the United States, residing at Jacksonville, in the county of Duval and State of Florida, have invented a new and useful Safety Bottle-Crate, of which the following is a specification.

The invention relates to improvements in shipping-crates for bottles.

10 The object of the present invention is to improve the construction of shipping-crates for bottles and to provide a simple, inexpensive, and efficient device capable of securely holding bottles and analogous receptacles in 15 a crate and preventing them during shipment from contacting with one another or the sides, bottom, or top of the crate and being broken or otherwise injured.

The invention consists in the construction 20 and novel combination and arrangement of parts, as hereinafter fully described, illustrated in the accompanying drawings, and pointed out in the claims hereto appended.

In the drawings, Figure 1 is a plan view of 25 a crate constructed in accordance with this invention. Fig. 2 is a horizontal sectional view. Fig. 3 is a vertical sectional view.

Like numerals of reference designate corresponding parts in the several figures of the 30 drawings.

1 designates a crate provided with a series of horizontal rods 2, arranged at intervals, disposed parallel with one another, and forming supports for horizontal clamping-bars 3, 35 which are adapted to engage bottles or analogous receptacles at opposite sides thereof, as clearly illustrated in Figs. 1 and 3 of the accompanying drawings. The clamping-bars and the rods, which are arranged at right angles to each other, divide the space within 40 the crate into a number of compartments or spaces for the reception of the contents of the crate. The clamping-bars are provided at opposite sides with curved recesses 4, conforming to the configuration of the curved sides 45 of the bottles and receiving elastic strips 5 of rubber or other suitable material, which directly engage the bottles. The elastic strips prevent the bottles from being broken in 50 straining the clamping-bars to the proper tension, and they securely hold the bottles and prevent them from slipping and contacting

with the crate or one another during shipment. The horizontal rods pass through perforations 6 of the clamping-bars and are secured in suitable perforations or sockets 7 of cleats 8, which are fastened within the crate at opposite sides thereof. 55

The crate may be of any desired size, and it may be provided at opposite sides with a pair of adjusting-screws 9, as illustrated in the accompanying drawings, or one or more adjusting-screws may be employed for the entire crate, according to the size thereof. Each adjusting-screw 9 engages a threaded opening of a frame or nut 10, and its inner end 11 is rounded and fits in a socket 12 of the adjacent clamping-bar. A washer 13, which is arranged on the smooth inner end of the adjusting-screw, is interposed between the clamping-bar and a radial series of arms 14, extending from the adjusting-screw at the inner end thereof and forming handles for enabling the screw to be readily rotated in adjusting the same. A plate 15 is secured to the outer face 75 of the end clamping-bar and is provided with a perforation to receive the inner end of the screw; but the sockets may be otherwise constructed, if desired.

The nut or frame 10 is provided with perforated ears and is secured to the inner faces of the sides of the crate by screws or other suitable fastening devices, which pass through the perforations of the ears. The plate is recessed to receive the inwardly-extending 85 enlargement or central portion of the nut, and it is provided with an opening 17, extending entirely through the side, for the passage of the screw to permit the latter to be adjusted to the desired extent. 90

The bottom of the crate is preferably lined with a sheet 18 of rubber or other elastic material to form a cushion for the bottles and prevent injury to the latter in handling the crate. 95

The invention has the following advantages: The crate is simple and comparatively inexpensive in construction and is capable of holding bottles and analogous receptacles stationary during shipment and of preventing them from contacting with one another and being broken or otherwise injured. The rubber strips of the clamping-bars firmly grasp the bottles and prevent them from slipping and contacting

ping, and they are also adapted to yield and prevent the bottles from being broken when the screws are adjusted to clamp the contents of the crate.

5 Changes in the form, proportion, and minor details of construction may be resorted to without departing from the spirit or sacrificing any of the advantages of this invention.

What I claim is—

- 10 1. The combination of a crate, a series of parallel clamping-bars, a series of horizontal rods rigid with the crate and arranged at right angles to and slidably supporting the clamping-bars, said bars and rods dividing the crate and forming separate bottle-receiving compartments or spaces, and an adjusting device for causing the clamping-bars to engage the entire contents of the crate, substantially as described.
- 15 2. The combination of a crate provided at one end with an opening extending entirely

through it, a series of parallel supporting-
rods rigid with the crate, a series of clamp-
ing-bars slidably mounted on the rods, said
rods and bars being arranged at right angles 25
to each other and dividing the crate into sep-
arate compartments, a nut mounted on the
crate and registering with the said opening,
and a screw engaging the nut and the adjac-
ent clamping-bar and arranged to extend 30
through said opening, whereby the end clamp-
ing-bar is adapted to be arranged close to the
end of the crate to adjust it to its full ex-
tent, substantially as described.

In testimony that I claim the foregoing as 35
my own I have hereto affixed my signature in
the presence of two witnesses.

GEORGE CLEAVELAND CHAPPELL.
